Primary Examiner—Carol Rademaker

(74) Attorney, Agent, or Firm—Knoble Yoshida & Dunleavy,
LLC(57) **CLAIM**

The ornamental design for a bottle, as shown and described.

DESCRIPTION

FIG. 1 is a perspective view of a bottle;

FIG. 2 is a front elevational view thereof, the rear elevational view being identical;

FIG. 3 is right side elevational view thereof, the left side elevational view being identical;

FIG. 4 is a top plan view thereof, shown at an enlarged scale; and,

FIG. 5 is a bottom plan view thereof.

The broken lines shown in the drawing views are included for the purpose of showing environmental structure that forms no part of the claimed design.
